UNITED STATES PATENT OFFICE.

HARRY L. LISSFELT, OF PITTSBURGH, PENNSYLVANIA, ASSIGNOR TO MACBETH-EVANS GLASS COMPANY, OF PITTSBURGH, PENNSYLVANIA, A CORPORATION OF PENNSYLVANIA.

DESIGN FOR A LAMP-SHADE.

45,641.

Specification for Design.

Patented Apr. 21, 1914.

Application filed February 28, 1914. Serial No. 821,807. Term of patent 14 years.

To all whom it may concern:

Be it known that I, HARRY L. LISSFELT, a citizen of the United States, residing at Pittsburgh, in the county of Allegheny and State of Pennsylvania, have invented a new, original, and ornamental Design for Lamp-Shades, of which the following is a specification, reference being had to the accompanying drawing, forming part thereof.

Fig. 1 is a plan view of a lamp shade showing my design, and Fig. 2 is a side elevation of such lamp shade.

I claim:

The ornamental design for a lamp shade, as shown.

HARRY L. LISSFELT.

Witnesses:

J. R. SCOTT,
JOHN H. FARRELL.
